United States Patent Office

Des. 208,490
Patented Sept. 5, 1967

208,490

DESK LAMP

Hiroshi Daito, Kyoto, Japan, assignor to Blackwell
Electronics Ind., Co., Ltd., Kyoto, Japan

Filed Dec. 19, 1966, Ser. No. 5,088

Term of patent 14 years

(Cl. D48—20)

FIG. 1

I claim:

The ornamental design for a desk lamp, as shown and described.
